UNITED STATES PATENT OFFICE.

FELIX FRANK, OF CLEVELAND, OHIO.

AIR-COOLING APPARATUS.

1,020,034.

Specification of Letters Patent. Patented Mar. 12, 1912.

Application filed December 10, 1909. Serial No. 532,389.

To all whom it may concern:

Be it known that I, FELIX FRANK, a citizen of the United States, residing at Cleveland, in the county of Cuyahoga and State 5 of Ohio, have invented certain new and useful Improvements in Air-Cooling Apparatus, of which the following is a specification.

This invention relates to air coolers and has for its object the provision of a comparatively simple and inexpensive device of this character especially adapted for installation in dwelling houses, churches, factories, hospitals, hotels and other places, for cooling and promoting the circulation of air 15 in warm weather.

A further object is to provide a cooling apparatus in which warm air is directed through a chamber containing ice or other refrigerant for delivery to the interior of a 20 room or other inclosure.

A further object is to provide an air cooler including inner and outer receptacles spaced apart to form an intermediate air circulating chamber, one of said receptacles being 25 provided with superposed ice and water receiving compartments respectively and having coil pipes extending therethrough and communicating with a discharge pipe.

Further objects and advantages will appear in the following description, it being understood that various changes in form, proportions and minor details of construction may be resorted to within the scope of the appended claims.

For a full understanding of the invention and the merits thereof and also to acquire a knowledge of the details of construction and the means for effecting the result, reference is to be had to the following description and 40 accompanying drawings, in which:

Figure 1 is a perspective view of an air cooler constructed in accordance with my invention; Fig. 2 is a vertical sectional view of the same; Fig. 3 is a vertical sectional view 45 showing the cooler in position on the roof of a building and employed for cooling the air in the several rooms of said building.

Corresponding and like parts are referred to in the following description and indicated 50 in all the views of the drawings by the same reference characters.

The device comprises an outer receptacle 5 of any suitable contour or cross sectional formation and preferably formed of spaced 55 plates between which is interposed a non-

heat conducting packing such as paper, sawdust, asbestos or similar material, indicated at 6. The top of the outer receptacle 5 is provided with an opening 7 to permit the passage of an inner receptacle 8, the latter 60 being provided with a marginal flange 9 adapted to bear against the top of the outer receptacle and by means of which the inner receptacle is suspended within the outer receptacle, as shown.

The inner receptacle 8 is preferably of the same shape as the outer receptacle and is spaced from the latter to form an intermediate air circulating chamber 10, said inner receptacle being provided with a transversely 70 disposed perforated partition 11 defining superposed compartments 12 and 13, one of which is adapted to contain a quantity of ice or other refrigerant and the other the water produced by the melting of said ice.

The inner receptacle 8 is provided with a lid or cover 14 having a plurality of perforations 15 formed therein, there being similar perforations 16 formed in the side walls of the compartment 12 so as to permit the passage of air through the ice in the compartment 12 into the intermediate air chamber 10 for the purpose of cooling the air prior to its delivery to the rooms of a building.

Disposed within the compartment 12 are a series of coil pipes 17 having funnel shaped mouths 18 and straight depending portions 19, which latter extend through the lower water receiving compartment 13 and are provided with flared portions 20, similar in construction to the flared portions 18 so that a portion of the air entering through the perforations in the cover 14 may be cooled without coming in direct contact with the ice. 90 If desired however, these coil pipes 17 may be dispensed with without departing from the spirit of the invention.

The intermediate portion of the partition 11 is preferably bent or dished downwardly 100 so as to facilitate the discharge of the water in the upper compartment 12 through the perforations in said partition, there being a drain 21 communicating with the lower compartment 13 to permit the discharge of the water therein, when desired.

The partition 11 is preferably extended laterally beyond the side walls of the inner receptacle 8 to form a circumferential trough 22 designed to catch any water that 110

may pass through the perforations 16 and direct the same into the compartment 13. A discharge pipe 23 communicates with the air chamber 10 at the bottom of the outer receptacle 5 and through which the cooled air is conducted to the interior of a room or other inclosure.

The pipe 23 may be connected directly to the bottom of the outer receptacle 5 or 10 through the medium of a relatively short flexible conductor, indicated at 24.

Supported on a spider 25 arranged above the discharge pipe 23, is a fan 26 which serves to draw the air through the perforations in the cover 14 and side walls of the inner receptacle 8 and force said air downwardly through the discharge pipe 23, thus to promote the circulation of air and cause the cool air to be continuously discharged 20 through said pipe into a room. If desired however, a suitable pump may be substituted for the fan 26, or said fan entirely dispensed with as may be found desirable or necessary to the proper working of the 25 device or the conditions under which it is used.

Secured to the top of the outer receptacle 5 are eyelets 27 having suspension cords or chains 28 secured thereto and adapted to be attached to a ceiling or other suitable support for the purpose of suspending the device within a room or other inclosure.

Thus it will be seen that the warm air entering through the perforations in the cover 14 and coming in contact with the ice or other refrigerant in the upper compartment 12 will be cooled and pass through the openings 16 in the walls of the inner receptacle and thence into the chamber 10 where it will pass downwardly through the 35 discharge pipe 23, as before stated, a portion of the air entering through the perforations in the cover 14 being directed through the coils 17 and flared portions 20 into the chamber 10 immediately above said 40 discharge pipe.

Where the device is to be used for cooling air in several rooms, the cooler is preferably supported on the roof of a building, in which event several discharge pipes 29 will 50 be connected with the chamber 10, some of said discharge pipes extending through the ceiling 30 and discharging into the adjacent room, and other of said pipes passing through the walls of the building and discharging into other rooms, as best illustrated in Fig. 3 of the drawings.

It is to be understood however that the cooler need not necessarily be suspended from a ceiling or supported on the roof of a 60 building as the same may be used with equally good results when positioned in a cellar, in which event a fan or pump will of course be employed for promoting the circulation of air within the several supply 65 pipes.

Having thus described the invention, what is claimed as new is:

1. An air cooler including a closed outer receptacle, an inner receptacle suspended within and spaced from the interior walls 70 of the outer receptacle to form an intermediate air chamber, said inner receptacle being perforated for a portion of the height thereof, a partition extending transversely across the inner receptacle beneath the perforated portion of the latter and defining superposed compartments, one of which is adapted to contain a cooling medium, a plurality of coils arranged within the cooling compartment and provided with oppositely 75 disposed flared mouths, a perforated cover forming a closure for the upper end of the inner receptacle, a discharge pipe communicating with the air chamber beneath the bottom of the inner receptacle, and means 80 for drawing air through the cooling chamber into the air chamber and forcing said air downwardly into the discharge pipe.

2. An air cooler including a closed outer receptacle, an inner receptacle suspended 90 within the outer receptacle and having its upper end open and its lower closed and spaced from the bottom of the outer receptacle, the side walls of said inner receptacle being perforated for a portion of the height thereof and spaced from the adjacent side walls of the outer receptacle to form an intermediate air chamber, a partition extending transversely across the inner receptacle 95 at the perforated walls thereof and defining superposed compartments, one of which is adapted to contain a quantity of ice and the other the liquid produced by the melting of said ice, a plurality of coils embedded in the ice and provided with oppositely disposed flared mouths, some of which extend through the bottom of the inner receptacle, a perforated cover forming a closure for the top of said inner receptacle, a discharge pipe 100 communicating with the air chamber directly beneath the closed end of the inner receptacle, and means for drawing air 105 through the inner receptacle into the air chamber and forcing said air downwardly into the discharge pipe.

3. An air cooler including a closed outer receptacle, an inner receptacle supported by and suspended within the outer receptacle and having its upper end open and its lower end closed and spaced from the bottom of 110 said outer receptacle, the side walls of the inner receptacle being perforated for a portion of their length and spaced from the inner walls of the outer receptacle to form a circumferential air chamber, a partition extending transversely across the inner receptacle and defining superposed compartments, one of which is adapted to contain 115 a cooling medium, a drain pipe communicating with the other compartment, a plu- 120

rality of coils arranged within the cooling compartment and provided with flared mouths, each coil terminating in a straight portion extending through the lower compartment of the inner receptacle and provided with a flared mouth projecting below the bottom of said receptacle, a discharge pipe communicating with the interior of the air chamber beneath the bottom of the inner receptacle, a drip trough surrounding said inner receptacle at the transverse partition thereof, a perforated cover forming a closure for the top of the inner receptacle, and means for drawing air through the cooling chamber into the air chamber and forcing said air downwardly into the discharge pipe. 15

In testimony whereof I affix my signature in presence of two witnesses.

Correction in Letters Patent No. 1,020,034.

It is hereby certified that in Letters Patent No. 1,020,034, granted March 12, 1912, upon the application of Felix Frank, of Cleveland, Ohio, for an improvement in "Air-Cooling Apparatus," an error appears in the printed specification requiring correction as follows: Page 1, lines 2-3, for the words "a citizen of the United States" read *a subject of the Emperor of Germany*; and that the proper corrections have been made in the files and records of this office and are hereby made in said Letters Patent.

Signed and sealed this 16th day of July, A. D., 1912.
